BLEEDER DEVICE INTERCONNECTING WALL HEADERS OF COKE-OVEN UNDERFIRING SYSTEM

Joseph van Ackeren, Pittsburgh, Pa., assignor to
Koppers Company, Inc., Pittsburgh, Pa., a cor-
poration of Delaware

Application August 14, 1945, Serial No. 610,693

6 Claims. (Cl. 202—151)

1

This invention relates to gas burners. More particularly the invention relates to gas burners for heating coke ovens in which waste flue gases are mixed with the gas to modify and control the combustion in oven flues.

Byproduct coke ovens are often heated by the combustion of coke oven gas in flues located on the opposite sides of the oven and separated from the oven by refractory walls. The coke oven gas normally has a B. t. u. value of 525 to 600 B. t. u.'s per cubic foot and will burn with preheated air with a comparatively short flame. It is the practice therefore to dilute the gas-air mixture being burned to modify the flame to produce a long flame combustion in order to secure a more uniform distribution of heat over the oven walls or in the oven flues. The gases for combustion may be diluted with products of combustion commonly called "waste gases" which are composed principally of carbon dioxide, nitrogen and water vapor as described in my Patent No. 2,306,678, granted December 29, 1942.

In the heating cycle of a coke oven, particularly an underjet oven of the type described in my Patent 2,306,678, the fuel and air for combustion are admitted through a series of burners mounted under the floor of the oven flues and distributed along the entire length of the oven. In the first half of the heating cycle the products of combustion pass upwardly through an "on" flue on one side of the oven wall and then pass up over the top of the oven and down through an "off" flue at the opposite side of the oven. The waste gases pass from the off flue through a regenerator below the oven, the heat of the regenerator being utilized for preheating the air for combustion. During the second half of the heating cycle the fuel gas and air are introduced at the bottom of the former off flue, pass up through the flue and cross over the oven and down through the former on flue to a regenerator. During the entire heating cycle waste gas is taken from the bottom of the off flue and mixed with a fuel gas-air mixture being burned in the on flue. The burner mixer tubes entering the bottom of the off flues do not have fuel gas passing through them during the off part of the cycle, but waste gases pass down through them during the off part of the cycle.

The burners for the on flues are connected by recirculation ducts with the corresponding burners of the off flues through which the waste gases are supplied to the on burners. All of the burners for the flues on one side of an oven are connected with a single gas distributing header. The burner aspirating nozzles have different gas ori-

2

fices at various points along the heating wall so that the suction created by different burner aspirators varies. The burners creating the greatest suction tend to draw waste gases into the distributing piping of the off burners and it is found that the acid constituents in the waste gases condense in the distributing piping and cause serious corrosion.

The primary object of the present invention is the provision of an apparatus for protecting fuel gas piping of a coke oven burner system to prevent corrosion of the piping.

Another object of the invention is the provision of an apparatus for alternately heating flues at opposite sides of a coke oven wherein the waste gas from an off flue is utilized in the gas being burned in the on flue, and the circulation of the heating gas is reversed during the heating cycle, to protect the burners from corrosion when they stand in the off position.

With these and other objects in view, the invention consists in the apparatus for protecting gas burner piping from corrosion which is hereinafter described and defined in the appended claims.

The various features of the invention are illustrated in the accompanying drawing which is a vertical sectional view of a portion of a byproduct coke oven battery showing the application of the gas burning equipment of the present invention to the coke ovens.

Referring to the drawing, coke ovens 10 are mounted in a refractory structure with heating flues 12 at each side of the oven and separated by refractory walls 14. The ovens are heated by combustion of gas within the flues 12. A common heating cycle consists of two heating operations, the first heating operation being carried on in an on flue with the waste gases passing upwardly through the flue, then through a cross-over flue 16 and down through an off flue 12. In the second half of the heating operation the gases are burned in the former off flue, pass up through the flue, then through the cross-over flue 16 and down through the former on flue.

The heating operation is carried out by burning gas which is supplied through a series of burners which are arranged at the base of the heating flues, there being twenty-eight burners in each heating wall of a typical battery of coke ovens, these burners being equally distributed along the length of the oven. Each burner consists of a mixing tube 18, an aspirator 20, a recirculating or connecting duct 22, and a branch fuel gas supply pipe 24. The fuel gas supply pipe has an inspirator nozzle 26 which

projects into a Venturi throat 28 of the aspirator 20. The branch supply pipe 24 is connected with a distributing pipe wall header 30 that is connected by a pipe 32 with a supply main 34. In the connecting pipe 32 is mounted a control valve 36 which is a plug type valve that is operated between off and on positions. The mixing tubes of each of the burners extend from the bottom of a flue 12 to the aspirator 20. The connecting or recirculating duct 22 extends from a mixing tube of a burner in one flue 12 across to the corresponding mixing tube for a burner in the flue at the opposite side of the coke oven. When gas is supplied to a burner tube the jet inspirator of the aspirator 20 creates a suction in the connecting duct 22 which acts to cause a portion of the waste gases flowing through an off flue to pass down through the mixing tube of the burners at the opposite side of the oven, thence through the connecting duct and into the aspirator 20 of the on burner. The waste gas is mixed with the fuel gases in the on burner mixing tube and flows from the upper end of the mixing tube into the bottom of the flue 12. The gas issuing from the mixing tube is met with a stream of preheated air which enters the bottom of a flue 12 through conduits 38 extending from the upper portion of regenerators 40. The aspirator of the burner is designed to draw into the mixing tube 18 a volume of waste gas about equal to the volume of fuel gas being supplied from the line 24. With a 550 B. t. u. coke oven gas being burned the diluted mixture reaching the top of the mixing tube 18 will have a B. t. u. value of approximately 250 B. t. u.'s per cubic foot. This gas which is diluted with waste flue gas gives a long flame combustion which is distributed throughout the width and height of the heating flue and thus provides a uniform and controlled heating of the walls of the coke oven. It is understood that the amount of fuel gas and flue gas may be varied in order to obtain the desired heating of the oven. The air for supporting combustion of the gas is supplied through a door 42 for each regenerator and passes into a duct 43 at the bottom of each regenerator. From the duct 43 the air passes up through a regenerator 40 to the offtake conduits 38 to support combustion in the flues 12. It will be understood that the air being supplied to the burner passes through two of the regenerators 40 and the waste gases passing out of the bottom of the flue 12 pass through two of the regenerators. The waste gases pass down through the regenerators into the ducts 43 and out through pipes 45 into a waste gas flue 44 which is connected with a stack (not shown). The air door to a regenerator is open when the regenerator is supplying air to a flue being heated and closed when waste gases are passing through the regenerator. When the waste gases pass through the regenerator the refractory brick in the regenerator are heated so that the air passing through the regenerator on the next cycle will be preheated to increase the temperature of the combustion gases passing through the flue.

The fuel gas valves 36 which control the supply of gas to all of the burners for heating the flues 12 are connected together by an operating cable 46 so that when the cable is moved to operate the valves these valves will move simultaneously to the various positions. As shown in the drawing, the valves 36 governing the supply of fuel gas to the flues of the right hand heating wall of each pair of heating walls are open, 75

while the valves 36 governing the supply of fuel gas to the flues of the left hand heating wall of each pair of heating walls are closed. When the valve levers 48 are moved by the cable 46 to the position in which the levers 48 extend to the left of the pipes 32, the valves 36 governing the supply of fuel gas to the flues of the left hand wall of each pair of walls are open and the valves 36 governing the supply of fuel gas to the right wall of each pair of walls are closed. When the valve levers 48 are set in a position so as to extend to the left of the pipes 32, the valve 36 at the left hand side will be open to supply gas to the flue at the left of the oven 10 and the valve on the right side will be set to close the supply of gas to the burners for the right flue 12. When gas is supplied for combustion in a flue, the flue and burner are referred to as an "on flue" and the "on burner," and at the same time the flue and burner on the opposite side of the oven are the "off flue" and "off burner." With the above described operation, therefore, the flue and burners alternately become "on" and "off" flues and burners.

25 The waste gases generally contain substantial amounts of acid constituents. For example SO₂, NO₂ and NO are generally present and sometimes HCl and SO₃ are present in small amounts. If these gases have an opportunity to condense in contact with any metal parts they actively corrode the metal and thus interfere with the proper operation of the burners.

Due to the construction and size of a coke oven it is necessary to supply more gas for heating the oven near its discharge end than near the pusher end. Accordingly, the nozzles of the aspirating burners near the discharge end of the oven are provided with larger orifices than are employed in the burners near the pusher end of the oven and these larger orifices create a larger suction than is created by the burners near the pusher end of the oven. As explained above, this suction action of the aspirators acts to draw the waste gases from a flue down through 35 the burner tubes 18 of the off burners into the connecting ducts 22. When a burner is operating in the off position no gas passes through the associated control valve 36 and at this time the burners producing the highest suction tend to draw waste gases from the off burners having a lower suction down through the branch pipes 24 into the distributing pipes wall headers 30. The pipes 24 and 30 have been found in practice to be sufficiently cool to condense acid constituents from the waste gases in the distributing piping and thus set up active corrosion in the piping.

To prevent the corrosion of the supply piping a cross tube 50 is connected between gas supply pipes 32 with an orifice disc 52 mounted therein. The opening in the disc is carefully proportioned so that sufficient gas will flow from the pipe 32 in which the control valve 36 is open to the associated pipe 32 in which the control valve 36 is closed to cause gas to flow through such other pipe 32 and thence upwardly through the branch pipes 24 to the recirculation ducts 22. This bleeder gas will mix with the waste gas passing through the ducts 22 and will flow upwardly through the mixing tubes 18 to burn in the on flues. Regardless of which one of the valve 36 is open, gas will pass to the branch pipes 24 of the off burners. The gas passing through the orifice 52 constitutes approximately 5% of the gas supplied to the burners but, since this gas goes

back to the mixing tubes of the on burners, no gas is lost. The pressure and volume of the gas flowing through the bleeder tube will overcome the unequal suction action of the various burner aspirators and prevent waste gas from entering into the branch pipes 24 and the supply pipes 38.

It will be understood that in the operation of the valves for reversing the flow of combustion gases through the flues in carrying out the heating cycle of the oven, the gas valves 36 and the air doors 42 are operated simultaneously to reverse the flow of heating gases. The air doors 42 for controlling the supply of air to the flues of each heating wall are connected by means of operating levers 54 with a cable 56. The means for operating the cables 56 and 46 are interconnected with a driving mechanism (not shown) to carry out the simultaneous movement of the air and gas valves. The heating operation of the ovens is continuous so that the ovens are being heated while they are being charged and discharged and during the coking operation.

While the preferred form of the invention has been described as applied to a burner equipment used to heat flues located on opposite sides of an oven, it is to be understood that the same burner arrangement may be used for heating that type of off and on flues which are located and arranged along one side only of a coke oven wall.

The preferred form of the invention having been thus described, what is claimed as new is:

1. A gas burning apparatus for heating coke ovens comprising: a series of horizontal coke ovens, a series of heating flues at each side of each oven, a series of aspirating burners positioned to introduce fuel gas into the flues at the side of an oven, said burners being connected in pairs with a connecting duct between the aspirators of each pair, one burner being an on burner for supplying gas to a flue while the other burner is an off burner and vice-versa, distributing pipes mounted below each coke oven, supply piping connecting the flue burners with a distributing pipe, a gas supply main, valved connections between the distributing pipes and the gas supply main, said valves being connected together and arranged to supply gas to the on burners of a pair while the gas to the off burners is cut off, a bleeder device for each pair of burners arranged to supply fuel gas from the supply main to the off burners when the on burners are operating, each bleeder device comprising an orifice disc mounted in a bleeder line connected between the burner distributing pipes to admit a limited supply of gas to the set of burners that are in the off position, and means for operating the valves to the on and off positions.

2. A gas burning apparatus for heating coke ovens comprising: a series of horizontal coke ovens, a series of heating flues at each side of each oven, a series of aspirating burners positioned to introduce fuel gas into the flues at the side of an oven, said burners being connected in pairs with a connecting duct between the aspirators of each pair, one burner being an on burner for supplying gas to a flue while the other burner is an off burner and vice-versa, distributing pipes mounted below each coke oven, supply piping connecting the flue burners with a distributing pipe, a gas supply main, valved connections between the distributing pipes and the gas supply main, said valves being connected together and arranged to supply gas to the on burners of a pair while the gas to the off burners is cut off, a bleeder device for each pair of burners ar-

ranged to supply fuel gas from the supply main to the off burners when the on burners are operating, each bleeder device being provided with a restriction which gives a limited open communication between the distributing pipes of a pair of burners, and means for operating the valves to the on and off positions.

3. In a regenerative horizontal coke-oven battery having vertically flued heating walls on opposite sides of horizontal coking chambers, the flues of the heating walls associated with a selected coking chamber being communicably interconnected at their upper parts into a first and a second set for operation in alternation with upflow combustion in one set of flues and concurrent downflow of the combustion products in the other set of flues, regenerators beneath the heating walls and coking chambers with regenerator division walls paralleling the coking chambers, fuel gas conduits each individual to a heating flue and extending upwardly through regenerator division walls to port into the lower parts of the heating flues, recirculation ducts connecting the fuel gas conduits for the flues of one set with the fuel gas conduits for the flues of the other set, jet means including gas nozzles individual to the respective fuel gas conduits for supplying fuel gas thereto, each jet means being disposed at the region of juncture of its fuel gas conduit with the recirculation duct therefor so as to reduce the pressure in said recirculation duct and thereby induce flow of waste gas from the bottoms of the flues of each set, when operable for downflow, through their idle fuel gas conduits and the recirculation ducts into the fuel gas conduits of the flues of the other set when concurrently operable for upflow combustion, a first supply pipe to which the gas nozzles associated with the flues of said first flue set are connected through branch pipes, a second supply pipe to which the gas nozzles associated with flues of said second flue set are connected through branch pipes, a first valve movable between an open and a closed position and governing the supply of fuel gas to said first supply pipe, a second valve movable between an open and a closed position and governing the supply of fuel gas to said second supply pipe, conduit connections between the first and second supply pipes having a restriction therein arranged to supply fuel gas to the first supply pipe at a predetermined restricted rate when said first valve is in closed position and said second valve is in open position, said conduit connections between said second and first supply pipes being arranged to supply fuel gas to said second supply pipe at a predetermined restricted rate when the second valve is in closed position and said first valve is in open position.

4. In a regenerative horizontal coke-oven battery having vertically flued heating walls on opposite sides of horizontal coking chambers, the flues of the heating walls associated with a selected coking chamber being communicably interconnected at their upper parts into a first and a second set for operation in alternation with upflow combustion in one set of flues and concurrent downflow of the combustion products in the other set of flues, regenerators beneath the heating walls and coking chambers with regenerator division walls paralleling the coking chambers, fuel gas conduits each individual to a heating flue and extending upwardly through the regenerator division walls to port into the lower parts of the heating flues, recirculation ducts connecting the fuel gas conduits for the flues of

one set with the fuel gas conduits for the flues of the other set, jet means including gas nozzles individual to the respective fuel gas conduits for supplying fuel gas thereto, each jet means being disposed at the region of juncture of its fuel gas conduit with the recirculation duct therefore so as to reduce the pressure in said recirculation duct and thereby induce flow of waste gas from the bottoms of the flues of each set, when operable for downflow, through their idle fuel gas conduits and the recirculation ducts into the fuel gas conduits of the flues of the other set when concurrently operable for upflow combustion, a first supply pipe to which the gas nozzles associated with the flues of said first set are connected through branch pipes, a second supply pipe to which the gas nozzles associated with flues of said second set are connected through branch pipes, a first valve movable between an open and a closed position and governing the supply of fuel gas to said first supply pipe, a second valve movable between an open and a closed position and governing the supply of fuel gas to said second supply pipe, and a pipe communication of predetermined restricted flow capacity through which fuel gas may flow between said first and second supply pipes.

5. In a regenerative horizontal coke oven having vertically flued heating walls on opposite sides of horizontal coking chambers, the flues of the heating walls on opposite sides of alternate coking chambers being connected at their upper parts by crossover ducts into a first set comprising the flues in one wall and a second set comprising the flues in the other wall for operation in alternation for upflow combustion in one wall and concurrent downflow of the combustion products in the other wall, regenerators beneath the heating walls and coking chambers with regenerator division walls paralleling the coking chambers, a supporting mat for the oven above an accessible passageway, fuel gas conduits each individual to a heating flue and extending substantially from the oven supporting mat upwardly through the regenerator division walls to port into the lower parts of the heating flues, recirculation ducts connecting the fuel gas conduits for the flues of the first set associated with a coking chamber with the fuel gas conduits for the flues of the second set associated with the same coking chamber, jet means including gas nozzles individual to the respective fuel gas conduits for supplying fuel gas thereto, each jet means being disposed at the region of juncture of its fuel gas conduit with the recirculation duct therefore so as to reduce the pressure in said recirculation duct and thereby induce flow of waste gas from the bottoms of the flues of each set, when operable for downflow, through their idle fuel gas conduits and the recirculation ducts into the fuel gas conduits of the flues of the other set when concurrently operable for upflow combustion, each heating wall having individual thereto a fuel gas supply pipe situated in said passageway and connected by branch pipes to all of the nozzles associated with said wall, each fuel gas supply pipe having individual thereto a valve movable between an open and a closed position and governing the supply of fuel gas to said supply pipe, the combination with the foregoing apparatus of means for preventing circulation of products of combustion through said fuel gas supply pipes and the branch pipes connected thereto between different nozzles associated therewith and thereby preventing corrosion of said pipes by said products of combustion, said means comprising for each of the fuel gas supply pipes associated with the heating walls forming a pair of heating walls conduit connections between the said fuel supply pipes having a flow restricting device therein for supplying fuel gas in a predetermined restricted flow to each one of the supply pipes when the valve associated therewith is in closed position and when the valve associated with the other supply pipe is in open position.

products of combustion, said means comprising for each pair of heating walls a communication between the fuel gas supply pipes associated with said heating walls and through which fuel gas may flow at a predetermined restricted rate.

6. In a regenerative horizontal coke oven having vertically flued heating walls on opposite sides of horizontal coking chambers, the flues of the heating walls on opposite sides of alternate coking chambers being connected at their upper parts by crossover ducts into a first set comprising the flues in one wall and a second set comprising the flues in the other wall for operation in alternation for upflow combustion in one wall and concurrent downflow of the combustion products in the other wall, regenerators beneath the heating walls and coking chambers, with regenerator division walls paralleling the coking chambers, a supporting mat for the oven above an accessible passageway, fuel gas conduits each individual to a heating flue and extending substantially from the oven supporting mat upwardly through regenerator division walls to port into the lower parts of the heating flues, recirculation ducts connecting the fuel gas conduits for the flues of the first set associated with a coking chamber with the fuel gas conduits for the flues of the second set associated with the same coking chamber, jet means including gas nozzles individual to the respective fuel gas conduits for supplying fuel gas thereto, each jet means being disposed at the region of juncture of its fuel gas conduit with the recirculation duct therefore so as to reduce the pressure in said recirculation duct and thereby induce flow of waste gas from the bottoms of the flues of each set, when operable for downflow through their idle fuel gas conduits and the recirculation ducts into the fuel gas conduits of the flues of the other set when concurrently operable for upflow combustion, each heating wall having individual thereto a fuel gas supply pipe situated in said passageway and connected by branch pipes to all of the nozzles associated with said wall, each fuel gas supply pipe having individual thereto a valve movable between an open and a closed position and governing the supply of fuel gas to said supply pipe, the combination with the foregoing apparatus of means for preventing circulation of products of combustion through said fuel gas supply pipes and the branch pipes connected thereto between different nozzles associated therewith and thereby preventing corrosion of said pipes by said products of combustion, said means comprising for each of the fuel gas supply pipes associated with the heating walls forming a pair of heating walls conduit connections between the said fuel supply pipes having a flow restricting device therein for supplying fuel gas in a predetermined restricted flow to each one of the supply pipes when the valve associated therewith is in closed position and when the valve associated with the other supply pipe is in open position.
